UNITED STATES PATENT OFFICE

WILLIAM E. LUNDGREN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

LOOM DRIVING MECHANISM

Application filed December 5, 1929. Serial No. 411,935.

This invention relates to looms and more particularly to mechanism for driving a harness motion of the type commonly referred to as a "Knowles" head.

5 It is the general object of my invention to provide an improved drive for such heads, so designed and constructed that a positive gear connection is provided which is readily adaptable to harness motions of different 10 widths, designed for different numbers of harnesses.

A further object is to provide a construction by which the necessary adjustment for changes in width may be quickly and easily 15 made and without removal or replacement of parts.

My invention further relates to arrangements and combinations of parts which will be hereinafter described and more particularly 20 pointed out in the appended claims.

A preferred form of the invention is shown in the drawings, in which

Fig. 1 is a side elevation, partly in section, of my improved driving mechanism;

25 Fig. 2 is a side elevation thereof, looking in the direction of the arrow 2 in Fig. 1;

Fig. 3 is a detail sectional side elevation, taken along the line 3—3 in Fig. 1;

Fig. 4 is a side elevation of the parts 30 shown in Fig. 1 but in different relative positions;

Fig. 5 is a side elevation of a gear cover to be used with my invention; and

Fig. 6 is a sectional elevation of the gear 35 cover and the loom frame on which it is mounted.

Referring to the drawings, I have shown portions of a Knowles head including a frame 10 in which harness jacks 11 are 40 pivoted at 12. The jacks are connected by links 13 to the usual vibrator gears 14 which alternately engage upper and lower cylinder gears 15 and 16 (Fig. 4) rotatably mounted in the frame 10. The gears 15 and 16 are 45 mounted on suitable supporting shafts and are connected by bevel gears 17, 18, 19 and 20 to an upright shaft 21 rotatable in a bearing 22 supported on the frame 10.

The gears 18 and 20 are axially adjustable 50 on the shaft 21 and may be secured thereon

by set screws 23. A collar 24 is also axially adjustable on the shaft 21 and may be secured by a set screw 25. The upper face of the collar 24 engages the under face of the bearing 22 and prevents upward movement of the shaft 21.

55 The lower end of the shaft 21 is received in a step bearing 30, secured by a set screw 31 to the outer end of a stud 32, which in turn is secured by a set screw 33 in an adjustable arm or support 35.

The support 35 is mounted for angular adjustment about the axis of a driving shaft 37 and may be secured in angularly adjusted position by clamping bolts 38 and 39 (Fig. 65 3). The bolt 38 extends through a segmental slot 40 in the arm 35 and the bolts 39 extend through short segmental slots 41 in the upper end of the arm 35 and also extend through selected slots 42 in the loom 70 side 44. The slots 42 are arranged in a segmental series about the axis of the shaft 37 as a center.

A pinion 50 is secured to the end of the driving shaft 37 and engages an intermediate gear 51 loose on the stud 22 and connected by a bevel gear 52 to a second bevel gear 53 rotatable about the axis of the shaft 21 and commonly secured to rotate therewith by a clutch collar 54.

75 A gear cover 60 (Figs. 5 and 6) may be secured by clamping bolts 61 extending through certain of the segmentally arranged slots 42. An outer gear cover 63 may be secured to the cover 60 by clamping bolts 64 extending through segmental slots 65 in the cover 63.

Having described the details of construction of my improved harness motion drive, the method of operation and advantages 90 thereof are as follows:

If a relatively narrow head with few harnesses is in use, the parts may assume the position shown in Figs. 1 and 2, in which the stud 32 is approximately vertically aligned 95 with the driving shaft 37. If a wider head is substituted, the upright shaft 21 will naturally be found further to the left, as shown in Fig. 4.

In order to provide a positive gear drive 100

with the parts as shown in Fig. 4, it is merely necessary to loosen the set screws 23—23 and 31, so that the bevel gears 18 and 20 may be adjusted axially on the shaft 21, and so that the step bearing 30 may be adjusted 5 angularly on the stud 32. The support 35 is then adjusted angularly about the axis of the shaft 37, so as to bring the step bearing 30 in vertical alignment with the new position of the upright shaft 21. The support 35 is then clamped to the loom side 44, the step bearing 30 is secured to the stud 32, and the bevel gears 18 and 20 are adjusted axially to engage the bevel gears 17 and 19 on 10 the shafts of the cylinder gears 15 and 16. The bevel gears 18 and 20 are then secured to the shaft 21, and the collar 24 is adjusted to take up vertical lost motion of the shaft 21.

20 By these simple adjustments, a positive gear drive is provided for the harness motion, regardless of its increase in width, and a similar adjustment may be secured for other harness motions of either greater or less width, all without removal or replacement of parts or substitutions therefor.

30 The gear covers 60 and 63 may also be conveniently adjusted to protect the operator in any angular position of the support 35 and gears mounted thereon.

35 Having thus described my invention and the advantages thereof, I do not wish to be limited to the details herein disclosed, otherwise than as set forth in the claims, but what I claim is:—

40 1. In a loom having a head motion with upper and lower cylinder gears, a substantially upright shaft and bevel gears connecting said shaft to rotate said cylinder gears, in combination, a driving shaft, a pinion on said shaft, an intermediate gear meshing therewith and mounted for adjustment about the axis of said driving shaft, and bevel gears connecting said intermediate gear with the lower end of said upright shaft.

45 2. In a loom having a head motion with upper and lower cylinder gears, a substantially upright shaft and bevel gears connecting said shaft to rotate said cylinder gears, in combination, a driving shaft, a pinion on said shaft, an intermediate gear meshing therewith, a supporting arm mounted for angular adjustment about the axis of said driving shaft, a bearing stud on said arm for said intermediate gear, and a bevel gear connection between said intermediate gear and said upright shaft.

50 3. The combination in a loom as set forth in claim 2, in which the stud is fixed in the supporting arm and supports an angularly adjustable step bearing for the lower end of said upright shaft, and in which the intermediate gear is freely rotatable on said stud.

55 4. The combination in a loom as set forth

in claim 2, in which the bevel gears on the upright shaft are axially adjustable on said shaft to establish driving connection with said cylinder gears in every operative position of said support and shaft.

5. The combination in a loom as set forth in claim 2, in which the bevel gears on the upright shaft are axially adjustable on said shaft to establish driving connection with said cylinder gears in every operative position of said support and shaft, and in which a collar is provided on said shaft and adjustable axially thereon to prevent axial lost motion thereof.

60 In testimony whereof I have hereunto affixed my signature.

WILLIAM E. LUNDGREN.
